UNITED STATES PATENT OFFICE.

CHARLES R. ELLACOTT, OF MONTREAL, QUEBEC, CANADA.

MACHINE FOR FORGING HORSESHOE-NAILS.

SPECIFICATION forming part of Letters Patent No. 257,302, dated May 2, 1882.

Application filed September 19, 1881. (No model.)

To all whom it may concern:

Be it known that I, CHARLES RICE ELLACOTT, of the city of Montreal, in the District of Montreal and Province of Quebec, Canada, have invented certain new and useful Improvements in Horseshoe-Nail-Forging Machines; and I do hereby declare that the following is a full, clear, and exact description of the same.

This invention relates to improvements in that class of machines for forging horseshoe-nails in which the same are wrought from a rod or bar; and it has for its object to insure a steadier and more positive action in the mechanism which feeds the bar forward to the anvil and dies where the nail is formed, so that there will be less wear and tear of the parts and always a certainty of the nails being forged to an even length of head.

It must be understood that while my improvements are represented as applied to a "Dodge" machine, they will be equally suitable for any of the improved machines now in use. In the present machines a large flat single or double spring having its lower end attached to a cross-bar in the front of the frame and its upper extremity bearing upon an arm impinging on a cam and projecting from the rock-shaft, from which reciprocating motion is imparted to the carriage upon which the rod is laid, is used to keep said arm close up against the cam which communicates motion to said rock-shaft. This I have found to be very objectionable, from the fact that when the carriage has brought the bar forward to the anvil and while the nail is being formed this spring is relaxed, and has not sufficient force or strength to keep the parts steady enough to insure the accurate forging of the nail, and when that part of the cam known as the "jerk" is reached there is always a certain amount of inaccuracy, which often allows the roll on the rock-shaft arm to jump over some distance or not follow closely the contour of the cam by any increase of speed, and thereby the rod is liable to become bent or crooked, and necessarily an imperfect nail is formed.

Now, by my invention the necessity for this spring and the objections arising from its use are done away with. I provide the rock-shaft,

which through an arm actuates the sliding carriage, with an additional arm projecting about at right angles to the present arm toward the center of the machine, and having mounted on its outer end a small roller, which impinges upon a cam which I mount on the same shaft, and arrange to rotate simultaneously with the ordinary cam operating the rock-shaft. This supplementary cam is of such configuration that when the ordinary cam presents its shortest side to the roller on the upwardly-projecting arm the impact will be perfectly close and beyond any liability of loosening, from the fact of the longest side of the supplementary cam being then in contact with the roll on the additional arm.

For full comprehension of my invention reference must be had to the accompanying drawings, in which similar letters of reference indicate like parts, and where Figure 1 is a plan showing the outline of a Dodge machine with my improvements applied; Fig. 2, a front view of the same, and Figs. 3 and 4 details of cams and arms actuated thereby.

A is the rock-shaft, extending across the front of the machine and working in centers fitted in same. This rock-shaft is provided with the ordinary arm, B, which is attached to and actuates the sliding carriage B', C being another arm, attached, as usual, to the same rock-shaft, its upper end being provided with a roller, c, which impinges against the periphery of a cam, D, mounted on a horizontal shaft, E, said shaft being rotated by power communicated through a train of gears, F F', from the main or driving shaft G in the usual way. As will be seen in Fig. 3, the cam D has on its periphery a cavity or indent, d, which is located just in front of that part known as the "jerk." When the roller c on the arm C comes to this cavity d it falls into the same, and produces in this manner a slight retrograde movement of the carriage and gripper holding the rod. By this movement the bending of the nail-rod which would otherwise be produced by the elongation of the metal is prevented. The mechanism now to be described obviates any chance of the roller c jumping over the cavity d, since the former is always held perfectly tight against the pe-

riphery of the cam D during its whole revolution.

In addition to the arms B and C, I mount firmly on the rock-shaft A, about at right angles to C, an arm, H, its outer extremity being provided with a roller, h. This arm H is formed, preferably as shown in Fig. 3, with a hinge, i, h being a spring or other device which will serve to adjust the roller and compensate for wear. The roller h impinges against the periphery of a supplementary cam, K, which I mount rigidly on the shaft E, alongside or close to the cam D. The contour and arrangement will be such that when that side of the cam D which is the least distance from the center of the shaft E is bearing on the roller c on the arm C the part of the periphery of the supplementary cam K which is farthest from the center of E will impinge on the roller h of the arm H, and vice versa, thus keeping the parts close in to one another and insuring accurate and positive motion throughout the entire revolution of the cam D, and enabling the machine to be run at a much higher rate of speed and with less power than are required for any other machine on the Dodge principle now in use; and thus the quantity of nails produced will be much greater in proportion to the increased rate of speed.

As shown in Figs. 3 and 4, I mount upon the side of the supplementary cam K a piece, k', forming the segment of a circle, that portion of its periphery which the projection from the cutter-shaft M first strikes against being slightly eccentric; and before the lump or projection L (shown more particularly in Fig. 3) is reached a friction-roll, l, mounted on the end of the projection from the cutter-shaft, commences to revolve, and the proper rate of speed relative to the difference in their diameters is attained thereby. When the throw takes place by the projection L coming in contact with the roll l the cutting-jaw receives its right amount of travel without any danger of an overthrow taking place, even when the machine is run at a very high rate of speed, this defect being specially noticeable when the old form of wiper is used to give motion to the cutter-shaft.

The general operation of a machine embodying my invention will be similar to that of any of the Dodge machines now in use, and need not be described; but it will be understood

from the foregoing and from the drawings that I obtain a much steadier and more positive motion and one requiring less power by the arrangement of my supplementary cam, in combination with the present rock and cutter shafts and by the abolition of the large spring and wiper, than can be produced by the old methods.

I am aware that cams are very generally used to give positive motion to reciprocating parts of machines for the manufacture of bolts and nuts, &c., and also that in the Patent No. 224,062, granted to Wills, February 3, 1880, a double system of cams is shown for positively operating a rock-shaft, an arm projecting from which actuates the slide-plate of a nail-finishing machine.

I am also cognizant of the fact that in Oehme's patent, No. 120,088, October 17, 1871, a pivoted lever having a small roller at its end working between two cams, each on separate shafts, and a similar lever with roller acting on the underside of the lower cam and kept up against it by a spiral spring, are used for operating the dies of a horseshoe-machine.

I wish it also to be understood that I do not claim any of the parts or devices shown in Dodge's patent, No. 25,183, August 23, 1859, as my invention, as already explained, is to overcome the inaccuracy heretofore found in the working of this Dodge machine, with a view to lessening the wear and tear and turn out a more perfect nail while the machine is running at a greater speed and with less power than heretofore.

What I claim, and desire to secure by Letters Patent, is as follows:

In a machine for forging horseshoe-nails, the combination, with the rock-shaft A, the arm C, and the cam D, mounted on the shaft E, of a supplementary cam, K, also mounted on the shaft E, and an arm, H, hinged at i to the rock-shaft A approximately at right angles to the arm C, provided with a roller, h, working on the periphery of said cam K, and adjusting device k, substantially as and for the purpose set forth.

CHARLES RICE ELLACOTT.
